Application August 3, 1953, Serial No. 371,962

12 Claims. (Cl. 294—63)

This invention relates to an improvement in stack lifter and deals particularly with an apparatus useful in lifting stacks of brick or the like. Various devices have been employed for lifting stacks of brick. Certain of these devices include elongated members having clamping device on one, or both sides thereof, and which are designed to extend through passages at the base of a stack of bricks or other such objects. If these devices are lifted the clamping means engages the bricks on one or both sides of the passages so that the load may be lifted.

The present device resides in a somewhat similar type of structure provided with a different operating mechanism from that which has been used in the past.

The object of the present invention lies in the provision of a series of clamping members which may be individually inserted in passages beneath a stack of bricks or the like and which include clamping means which are actuated by the weight of the material being lifted. In other words the clamping means are urged against the bricks on one or both sides of the passage when the clamping members are lifted by a separable lifting mechanism. The weight of the load actually operates the clamping means.

A feature of the present invention lies in the provision of a series of elongated clamping devices, each having a series of longitudinally clamping members thereupon. These clamping members are actuated by projections extending above the level of the clamping members and individually engaging bricks, or the like, located above the passage in which the clamping device is located. These projections engage the load prior to the engagement of the load by the clamping device in general and the weight of the load presses the projections downwardly relative to the remainder of the clamping device as the clamping device is lifted. Each projection controls a suitable clamping mechanism and these clamping mechanisms are spaced so that the load may be lifted in spite of the fact that the degrees to which the projections are depressed and the extent to which the individual clamping members may move invariably.

A further feature of the present invention resides in the provision of a series of clamping members of elongated form having a series of individual longitudinally spaced clamping members attached thereto and in providing in preferred form a plurality of clamping member operating projections connected to each clamping member. As a result, if one projection enters a gap between the bricks or enters a space from which a brick is missing or is broken, the clamping member may still operate through operation of the other projection.

These and other objects and novel features of the invention will be more clearly set forth in the following claims.

In the drawings forming a part of the specification:

Figure 1 is top plan view of a series of clamping devices connected to a lifting means and showing the relationship between the clamping devices and the bottom tiers of the bricks or like.

2

Figure 2 is a perspective view of the portion of the lifting apparatus used in conjunction with the individual clamping device.

Figure 3 is a side elevational view of the individual clamping device in position beneath a series of bricks and showing the lifting device being lowered for engagement with the clamping device.

Figure 4 is an enlarged elevational view showing a pair of clamping devices connected to a portion of the lifting device, the clamping device in clamping position.

Figure 5 is an end elevational view of one of the clamping devices.

Figure 6 is an end elevational view of another of the clamping devices. This device is used on one side of the stack.

Figure 7 is a perspective view of an end portion of one of the clamping devices.

In general the apparatus includes a lifting device which is indicated in general by the letter A; clamping devices B which are designed to extend between tiers of brick or the like to clamp against both sides of the passages in which the clamping devices are located; and end clamping devices C which are similar to clamping device A but clamp in one direction only. The clamping devices B and C are connected to the lifting device A during the lifting operation and are designed to lift a load of brick or stack of bricks D. The lifting device A is best illustrated in Figure 2 of the drawings and in the particular form illustrated comprise an elongated rectangular bar 10 having brackets 11 slidably supported thereupon. The brackets 11 are shown as being rectangular in outline and have rectangular apertures 12 extending therethrough to accommodate the bar 10. The apertures 12 are large enough so that the brackets 11 may be adjusted longitudinally of the bar 10. Thumb screws 13 or other suitable means are provided for holding the brackets 11 in adjusted position.

Each bracket extends downwardly from the bar 10 and is provided with a rectangular aperture 14 which extends through the bracket at right angles to the aperture 11 and below the level thereof. These apertures 14 are designed to accommodate the ends of the clamping devices B as will be later described in detail.

A rectangular collar 15 encircles each end of the bar 10 and is held in place by a bolt 16. A cable 17 is secured to each collar 15 in any suitable manner and the cables 17 are connected to a suitable hoisting mechanism. Each of the cables 17 is normally lifted simultaneously so that the load remains in proper position.

The clamping devices B are shown as best illustrated in Figures 5, 6 and 7 of the drawings taken in conjunction with their operation as illustrated in Figure 4. The body of each clamping device includes an elongated I-beam 19 having an upper web 20, a lower web 21 and an intermediate vertical connecting web 22. The top and bottom flanges 20 and 21 are cut away at each end of the I-beam so that the web 22 forms a projection 23 of proper shape to fit into the aperture 14 of a bracket 11 of the lifting device A.

A series of hinges are secured to the surface of the web 20, one hinge plate 24 being secured to the under-surface 25 of the web on one side of the center web 22 and a similar hinge plate 26 being secured to underface of web 20 on the opposite side of the center web 22. A second hinge plate 27 is pivotally connected to hinge plate 24 by a hinge pivot 29 and a similar hinge pivot 30 connects a hinge plate 26 to a cooperable hinge plate 31. The hinge plates 27 and 31 are normally suspended in substantially vertical relation when the clamping device is not in use.

An angle bracket 32 is bolted or otherwise secured at 33 to the hinge plate 27 and includes a flange 34 in sur-

face contact with the plate 27 and a second flange 35 at substantially right angles to the flange 24. Each flange 35 is notched to accommodate one or more spaced cylindrical plungers 36 which extend upwardly through the flange 20 of the I-beam. The notch in each flange 35 permits tipping of the angle bracket 32, as illustrated in Figure 4. A pin 37 extends through each plunger 36 beneath the flange 20 and a spring 39 is interposed between the pin 37 and a washer 40 encircling the plunger 36 immediately above the flange 35.

An angle bracket 41 has one flange 42 secured to the web 22 of the I-beam and a second flange 43 extending at right angles thereto. The flange 43 is provided with apertures 44 therethrough to slidably accommodate the corresponding plunger 36. A spring 45 encircles the lower portion of the plunger 36 between the undersurface of the flange 35 and the flange 43. This spring 45 is weaker than the spring 39 previously described but tends to return the flange 35 to horizontal position when downward pressure on the plunger is relieved.

A spring strip 46 is secured to the flange 34 of the angle bracket 32 and is bolted at 47 to a block like pad 49 of rubber or other resilient means. This pad 49 and the spring strip 46 flexes sufficiently to engage against bricks or other means we will be later describing. A similar arrangement is provided on the opposite side of the center web 22 of the I-beam. A plunger 50 extends through a suitable aperture 51 in the web 20 and through a suitable guide aperture 52 in an angle bracket 53 secured to the web 22. An angle bracket 54 is bolted at 55 to the hinge plate 31 and is properly notched to straddle a plurality of such said plungers 50. In other words each bracket 54 straddles at least one plunger 50, and the notched bracket 54 tips or pivots at an angle as illustrated in Figure 4 to perform the lifting operation as herein described.

A relatively strong spring 56 is interposed between a washer 57 overlying the bracket 54 and a pin 59 extending through the plunger 50. A relatively weak spring 60 is positioned between the angle bracket 53 and the angle member 54 to return this latter angle member to horizontal position when the device is not in use. The spring plate 61 is bolted to the vertical flange of the angle bracket 54 and is bolted at 62 to a block like pad 63 of resilient material designed to engage against the bracket.

In Figure 6 of the drawings a clamping device C is illustrated. This clamping device C is quite similar to half of the device B. One such clamping device C is used at each side of the stack of bricks D to be lifted.

The device C includes a channel beam 64 having an upper flange 65, a lower flange 66, and a connecting base web 67. This web 67 projects beyond the upper and lower flanges 65 and 66 to provide a projecting end 69 similar to the projection 23 of the previously described beam 19 at each end thereof. The projection 69 is designed to slide into any aperture 14 in a suitable bracket 11.

An angle member 70 is secured to the web 67 and is provided with spaced apertures 71 which are aligned with apertures 72 in the flange 65 of the beam 64. Each aperture is designed to accommodate a slideable plunger 73. A hinge plate 74 is secured to undersurface of flange 65. A cooperable hinge plate 75 is connected to hinge plate 74 by a hinge pivot 76. The hinge plate 75 accommodates an angle member 77 of sufficient length to bridge a plurality of plungers 73. The angle member 77 is provided with a vertical flange 79 and a horizontal flange 80. A flange 80 is notched to accommodate one or more plungers 73.

A spring 81 is interposed between a washer 82 encircling the plunger 73 and a pin 83 extending through the plunger. A lighter spring 87 encircles the plunger 73 and the angle bracket 80.

A resilient sheet 84 or spring metal, or the like, has its upper end bolted to the vertical flange 79 and the hinge 75

plate 75 and is bolted at 85 to a block 86 of rubber or other resilient material. The spring strip 84 and the resilient block 86 flex and compress to fit firmly against a row of bricks in clamping position.

In actual practice the beams 19 and 64 have a number of similar clamping units throughout the length thereof. Figure 7 shows one unit in which the block 49 is controlled by two spaced plungers 36, either of which is capable of pivoting the block into clamping position. The block 63 on the opposite side of the beam is actuated by spaced plungers 50 which are arranged in opposed relation to the plungers 56. From Figure 1 of the drawings it will be shown that eight such units are provided in the particular arrangement illustrated. In the form shown, each of the units is approximately the length of a brick, or block, such as 87, so that individual bricks may be individually clamped to compensate for variation in the size of the bricks. However, this is not essential as the spring plates, such as 46, 61, and 84 tend to compensate for irregularities of the bricks.

As shown in the drawings, the stack of bricks D is built up by placing spaced tiers of bricks in parallel relation on edge upon the ground or floor. In the form shown, two rows of bricks 89 and 90 are supported in spaced relation to a second pair of rows of bricks 91 and 92. This provides a channel or passage 93 between the bricks 90 and 91. An additional pair of rows of bricks are shown at 94 and 94'.

The next layer of bricks is positioned at right angles to the lower rows and the end bricks of this layer project beyond the rows 89 and 94 to provide hanging ledges 95 and 96. Clamping devices B are inserted in the passages 93 and 97 and clamping devices C in place and beneath the overhanging ledges 95 and 96, while the stack of bricks include additional layers superimposed upon the lowermost layers, these have not been described in detail because the arrangement of these upper layers form no part of the system.

When the individual clamping devices B and C have been inserted in the manner shown in Figure 3 the lifting device A is lowered. One member, such as that shown in Figure 2, being on each side of the stack of bricks D. The brackets 11 are properly spaced to engage the ends of the clamping devices which project beyond the sides of the stack of bricks.

When the brackets have been attached to the projecting ends 23 and 69 of the units B and C, respectively, as indicated in Figure 4 of the drawings, a lifting load may be applied to the cable 17. As the clamping units are lifted upwardly the projections 36, 50, and 73, which comprise the upper ends of the plungers identified by the same numerals, engage against the bricks of the second layer 99. The weight of the stack of bricks holds the plungers from upward movement and continued upward movement of the clamp devices acts to swing the clamp blocks 49, 63, and 86 against the lower rows of bricks. This clamping action continues until the ends of the plungers are flush with the channel and I-beam webs. Further upward movement of the cables then causes the lifting of the entire stack of bricks D. It will be noted that by providing a plurality of upward projection or plunger ends for operating each clamping member, the clamp operation will function even though a brick or two is out of place or broken. Therefore, the proper lifting of the entire stack is insured.

When the load is lowered, the lowermost row of bricks contacts the floor or ground and further lowering of the cables 17 acts to permit the beams to lower relatively to the projections. As a result the clamping devices are released. The lifting devices A may then be removed and the various members B and C may be taken from the load.

In accordance with the patent statutes, the principles of construction and operation of the lifting device have been described and while it has been endeavored to set forth the best embodiments thereof, it is desired to have

it understood that obvious changes may be made within the scope of the following claims without departing from the spirit of the present invention.

I claim:

1. A lifting apparatus for lifting a stack of bricks having spaced rows of bricks therebeneath, the apparatus including in combination a series of elongated members separately insertable between said rows of bricks, lifting means engageable with the ends of said elongated members, a plurality of plungers supported by said elongated members, pivotal bracket elements supported by said elongated members and connected to said plungers, and pivotal clamp blocks supported by said bracket elements on the separately insertable elongated members and independently operable by the weight of a load acting on said plungers after the elongated members are lifted but before the weight of a load is taken up by the elongated members for clamping the rows of bricks therebetween.

2. An apparatus for lifting stacks of bricks and the like, each stack including a body of material having spaced elongated supporting legs with open passages therebetween, the lifting apparatus including in combination elongated clamping devices insertable through said passages and provided with extending ends, adjustable lifting means engageable with the said ends of said elongated members, pivotally mounted clamping means on said elongated members, hinged bracket elements mounting said clamping means on said elongated members, and a plurality of plunger means connected to said bracket elements and extending through said elongated members and adapted to be actuated by the weight of the stack of material above said passages for actuating said pivotal clamping means.

3. The construction described in claim 2 and in which said plunger means for actuating said clamping means are spaced longitudinally along said members.

4. The construction described in claim 2 and in which said clamping members are clamping blocks longitudinally spaced along opposite sides of said elongated members.

5. The construction described in claim 2 and including a plurality of longitudinally spaced clamping members pivotally mounted on said elongated members comprising the clamping members, previously described, and including longitudinally spaced plunger means comprising 45 said means for actuating said clamping members.

6. An element for clamping the sides of a passage beneath a stack of bricks or the like including in combination an elongated member, pivotal clamping means mounted on opposite sides of said elongated member, 5 hinged bracket means mounted on said elongated member for supporting said clamping means, and reciprocal projecting means supported by and projecting above said elongated member for engaging the top of the passage and connected to said bracket means for actuating said pivotal clamping means.

7. The construction described in claim 6 and in which the clamping means are longitudinally spaced.

8. The construction described in claim 6 and in which said projecting means are longitudinally spaced.

15 9. The construction described in claim 6 and in which said clamping means and said projecting means are longitudinally spaced along said elongated members.

10. A device for clamping against the sides of a passage beneath a stack of bricks or the like, the device including in combination an elongated member having a substantially flat upper surface, elongated clamping means on said elongated member beneath said surface and extendable laterally from said elongated member, a resilient bar means connected to said clamping means, plunger means extending through the said upper surface and connected to said resilient bar means and thereby to said clamping means for actuating the same, said plunger means projecting above the upper surface of said elongated member.

20 11. The construction described in claim 10 and in which said clamping means are longitudinally spaced along said elongated member.

25 12. The construction described in claim 10 and in which said plunger projecting means are spaced longitudinally along said elongated members.
